Des. 206,438
Patented Dec. 13, 1966

206,438

CONTROLLER CABINET FOR DATA PROCESSING SYSTEM OR SIMILAR ARTICLE

Pierre L. Crease, Kettering, Ohio, assignor to The National Cash Register Company, Dayton, Ohio, a corporation of Maryland

Filed July 8, 1965, Ser. No. 86,080

Term of patent 14 years

(Cl. D26—5)

FIG. 1

FIG. 2

FIG. 3

FIG. 1 is a right front perspective view of a controller cabinet for data processing system or similar article showing my new design;

FIG. 2 is a rear elevational view; and

FIG. 3 is a left side elevational view thereof.

I claim:

The ornamental design for a controller cabinet for data processing system or similar article, as shown.
